H. R. JOHNSON.
LINGERIE CLASP.
APPLICATION FILED JAN. 21, 1922.

Patented July 25, 1922.

Harold R. Johnson INVENTOR.

Joseph A. Miller BY ATTORNEY.

U. S. PATENT OFFICE.

GEWOOD, RHODE ISLAND, ASSIGNOR TO OSCAR R.
ANY, OF CRANSTON, RHODE ISLAND.

LINGERIE CLASP.

Specification of Letters Patent. Patented July 25, 1922.

Filed January 21, 1922. Serial No. 530,822.

ad of the
at 11 and

is formed so as to snap over the curved end 6 of the other member of the clasp. As depicted in the drawings, the part 3 is arched in form so that its convex side will engage the member 10 and not only tension the latter, but also act to effectively grip the lingerie, thereby preventing slippage between the clasp and the material. Further as illustrated in the drawings, and in order to increase the holding of the clasp relative to the lingerie the part 3 is formed with preferably four out-turned lips 12, the latter extending beyond the convex side of the member 3 so as to form distinct, spaced or separated gripping elements, which literally bite into the material so as to not only extend into same, but to also cooperate with the member 10 in forcing the material against this member 10.

From the foregoing it will be seen that the doubled strip not only forms a hinge knuckle at its doubled end 7, but also and at the same time forms the tensioning and material gripping member 3, thus providing not only a simple structure, but also one in which the two parts 2 and 3 of one member of the clasp are integrally connected at one end. Similarly the curved end 6 not only affords a means for holding the part 3 in position, but also forms a part into engagement with which the curved end 11 of the member 10 snaps, the two ends of the member of the clasp constituted by the parts 2 and 3 thereby functioning in a dual manner in each instance.

Having thus described my invention, what I claim as new and desire to secure by Letters Patent is:-

1. In a clasp, a pair of members one of which includes a strip of metal doubled upon itself and having the end of its doubled part curved and formed with a slot, the end of the outer part of the strip being curved and formed with a V-tongue and the opposite end of the strip being formed with a V-notch 95 receiving the tongue, the inner part of the doubled strip being bowed outwardly away from the outer part, the other member having a curved tongue at one end hingedly engaged in said slot and having its opposite end curved so as to snap into engagement with said curved end of the outer part of the strip.
2. In a clasp, a pair of members one of which includes a strip of metal doubled 110

upon itself and having the end of its doubled part slotted, the inner of the doubled parts being bowed outwardly, means to secure the ends of the strip together, the other member having a tongue at one end hingedly engaged through the slot, and means to latch the opposite end of said other member to the first member.

3. In a clasp, a pair of members one of which has a doubled slotted end and a curved end, the other member having a tongue at

one end hingedly engaged in the slot and having its opposite end formed to snap into engagement with the curved end of the first member.

In testimony whereof I have signed my name to this specification in the presence of two subscribing witnesses.

HAROLD R. JOHNSON.
